US00D914817S

(12) **United States Design Patent** (10) Patent No.: **US D914,817 S**
(45) Date of Patent: **** Mar. 30, 2021**

(54) **GOLF CLUB HEAD**(71) Applicant: **PARSONS XTREME GOLF, LLC**,
Scottsdale, AZ (US)(72) Inventors: **Robert R. Parsons**, Scottsdale, AZ
(US); **Michael R. Nicolette**, Scottsdale,
AZ (US); **Bradley D. Schweigert**, Cave
Creek, AZ (US)(73) Assignee: **PARSONS XTREME GOLF, LLC**,
Scottsdale, AZ (US)(**) Term: **15 Years**(21) Appl. No.: **29/702,869**(22) Filed: **Aug. 22, 2019****Related U.S. Application Data**(60) Division of application No. 29/622,326, filed on Oct.
16, 2017, now Pat. No. Des. 863,478, which is a
continuation-in-part of application No. 29/618,845,
filed on Sep. 25, 2017, now abandoned, which is a
continuation-in-part of application No. 29/611,387,
filed on Jul. 20, 2017, now abandoned, and a
continuation-in-part of application No. 29/614,849,
filed on Aug. 23, 2017, now abandoned.(51) LOC (13) Cl. **21-02**

(52) U.S. Cl.
